George Stump

UNITED STATES PATENT OFFICE.

GEORGE STUMP, OF NEW YORK, N. Y.

IMPROVEMENT IN EVAPORATING-PANS FOR SACCHARINE LIQUIDS.

Specification forming part of Letters Patent No. 35,844, dated July 8, 1862.

To all whom it may concern:

Be it known that I, GEORGE STUMP, of the city, county, and State of New York, have invented a new and Improved Evaporating-Pan; and I do hereby declare that the following is a full, clear, and exact description of the same, reference being had to the accompanying drawings, forming a part of this specification, in which—

Figure 1 represents a longitudinal vertical section of my invention, the line xx , Fig. 2, indicating the plane of section. Fig. 2 is a transverse vertical section of the same, taken in the plane indicated by the line yy , Fig. 1.

Similar letters of reference in both views indicate corresponding parts.

This invention consists in the arrangement of a double-chambered bed-plate in combination with a double set of **C**-shaped tubes, which rise from a detachable tube-sheet in the interior of the pan, and which form a double connection between the two chambers of the bed-plate in such a manner that steam introduced into one of said chambers passes through said **C**-shaped tubes into the other chamber, and that by the peculiar arrangement of said heating-tubes an extensive heating-surface at different levels of the liquid is obtained, and at the same time the water which may condense in said tubes readily runs off into one or the other of the chambers, and causes no injury to the apparatus by freezing, &c., and, furthermore, all the tubes can be easily cleaned on the outside without breaking any joint whatever, and on the inside by removing the tube-sheet.

To enable those skilled in the art to make and use my invention, I will proceed to describe its construction and operation with reference to the drawings.

The pan A is made of copper or any other suitable material, and it is provided with a flange, a , at its bottom edge, so that the same can be conveniently fastened down upon the bed-plate B by means of screw-bolts b , or in any other desirable manner. The pan is open at its bottom, and it is fastened down upon the tube-sheet C, which is inserted between the bed-plate B and the bottom edge or flange, a , of the pan. The screw-bolts b pass through the flange a , tube-sheet C, and bed-plate B, and suitable packing-pieces introduced between the several surfaces render the joints

tight when the bolts b are screwed up. The bed-plate B is provided with two longitudinal chambers, D D', and tubes E E', the ends of which are inserted into the tube-sheet C, form a connection between the two chambers. The tubes E E' are bent in the form of the letter **C**, and the bends of the tubes E are higher and wider than the bends of the tubes E', so that convenient access can be had to the outer surfaces of both sets of tubes when it is desired to clean them.

F is the steam-pipe, through which steam is admitted into the chamber D', and this steam passes readily and without obstruction through the tubes E E' into the chamber D, and out through the discharge-pipe G. Suitable cocks regulate the current of steam through the apparatus.

The water which may condense in the heating-tubes E E' runs down into the chambers D D', whence it may be readily and easily removed, and the condensed water is not permitted to accumulate in the heating-tubes, where it would be liable, particularly in the cold season, to cause a serious obstruction and to prove injurious to the apparatus. At the same time by the application of the double set of **C**-shaped tubes a very extensive heating-surface is obtained, and the heat acts on the surrounding liquid at different levels, so that the contents of the pan can be brought to and kept at the desired temperature with a comparatively small expenditure of steam.

The tubes E E' are rigidly inserted into the tube-sheet, and consequently there is no joint through which a leakage might take place, and the only joint which has to be kept tight is on the outside, where easy access can be had at all times during the operation of boiling, as well as if the pan is cold. By breaking the joint access can be had to the interior of the chambers D D' and of the heating-tubes E E' whenever it becomes necessary to clean the same; and, finally, if any part of the tube-sheet or of the heating-tubes should become defective it can easily be repaired, or if after a certain time the tube-sheet or heating-tubes should be worn out it can easily be removed and replaced by a new one without disturbing any portion of the pan.

Having thus fully described my invention, what I claim as new, and desire to secure by Letters Patent, is—

1. The arrangement of the double-chambered bed-plate B in combination with the detachable tube-sheet C, double set of C-shaped heating-tubes E E', and pan A, all constructed and operating substantially as and the purpose shown and described.

2. The double set of C-shaped heating-

tubes E E', bent at different heights and at different widths, in combination with the pan A, as and for the purposes specified.

GEORGE STUMP.
